VALVED SELECTIVE SOUND CONTROL DEVICE

Filed July 1, 1946

UNITED STATES PATENT OFFICE

2,541,164

VALVED SELECTIVE SOUND CONTROL DEVICE

Charles Huenlich, Bloomfield, N. J., assignor to
 Thomas A. Edison, Incorporated, West Orange,
 N. J., a corporation of New Jersey

Application July 1, 1946, Serial No. 680,605

2 Claims. (Cl. 181—18)

1

This invention relates to sound-control devices for phonographic transcribing machines of the acoustical type, and more particularly to an improved such device which is adapted to enable a transcriber to listen to the reproduced sounds from a loudspeaker horn or privately from a headset. More especially, my invention relates to a novel such sound-control device which is adapted for selectively connecting the horn or headset to the source of sound and for controlling the tonal character of the sound.

It is an object of my invention to provide a unitary device for selectively coupling an acoustical source to different sound receivers and for modifying the character of the sound to each receiver.

It is another object to provide such an acoustical device which has a single control movable into different positions within one range of travel thereof for differently coupling the source to one sound receiver and into different positions within another range of travel thereof for differently coupling the source to a second sound receiver.

Other objects are to provide a combined sound-selecting and -modifying device of novel form which is simple in its construction and highly effective for controlling the tonal character of the reproduced sounds of transcribing machines.

These and other objects and features of my invention will be apparent from the following description and the appended claims.

In the description of my invention reference is had to the accompanying drawings, of which:

Figure 1 is a perspective view of a transcribing machine incorporating my invention;

Figure 2 is an end view of the sound-control device of my invention;

Figure 3 is a side elevational view of this sound-control device;

Figure 4 is a section on the line 4—4 of Figure 2;

Figure 5 is a section on the line 5—5 of Figure 3;

Figure 6 is a fractional right-hand view of the structure of Figure 5; and

Figure 7 is a section on the line 7—7 of Figure 3.

The transcribing machine shown in Figure 1 has a cabinet 10 openable at the front in which there is housed an operating mechanism of conventional design. This mechanism includes a record support shown for example as a mandrel 11. This mandrel is journaled at its left end and is free at its right end to receive a cylindrical record 12. Mounted slidably on cross rods of which one appears as 13 is a carriage 14 having

an arm overhanging the record. In this arm is mounted an acoustical-type sound reproducer 15 of a type, for example, such as described in Holland Patent No. 1,207,404. Also on the carriage there is a depending arm 16 adapted to overlie a so-called index slip 17a mounted in a holder 17, to indicate the place on the record whereat the dictator may have made corrections or other notations. The reproducer 15 is adjustable into and out of coaction with the record by any suitable standard means known in the art controlled as by a lever 18. During operation the record is rotated and concurrently the carriage is fed to the right along the record so that the reproducer will track the spiral grooves on the record to reproduce the recorded matter. These reproduced sounds are fed through a tubular neck 19 at the top of the reproducer (Figure 4) and are conducted therefrom either to an acoustical headset 20 or a loudspeaker horn 21 as is herein next described.

Mounted on the reproducer is a sound-control device 22 according to my invention. This control device comprises a tubular housing 23 which telescopes the tubular neck 19 and is retained thereon by a set screw 24. The housing has two outlets 25 and 26 leading from the side thereof at points in a common plane transverse to the axis of the housing. These outlets are spaced about the axis of the housing at an angle of approximately 90° from each other. The outlet 25 is coupled acoustically by an armored flexible tube 27 to the horn 21. This horn is bracketed at 28 to a vertical support rod 29 which is slidably mounted for vertical adjustment on the forward end of a laterally-swinging arm 30 that overhangs the cabinet and is pivoted to the back side thereof (the pivoting being not necessary herein to show). For retaining the rod 29 in its vertically-adjusted position there is a hand screw 30a. The other outlet 26 is acoustically coupled by a flexible rubber tube 31 to the headset 20. Typically such headset comprises two curved tubes 20a pivoted to a T-fitting 20b and having rubber-tipped ends 20c adapted to fit the ears of the transcriber.

The housing 23 has an interior bore 32 which is preferably countersunk at the top to provide the housing with an interior bevel 33. The exterior end face 34 of the housing is also beveled to have a frusto-conical shape. Snugly rotatably fitting the bore 32 is a cylindrical valve 35 which has a knurled head 36 provided with an annular rib 37 at the base. The under side of this rib 35 seats slidably on the bevel 33 and the outer side

thereof forms an even extension of the frusto-conical face 34. The valve member is retained in place by a screw 38 which is threaded through the wall of the housing and engages a peripheral slot 39 in the valve. This slot also defines the overall range of angular adjustment of the valve, this range being preferably about 170°.

The valve has a central chamber 40 extending from the bottom to near the top thereof. In this chamber, preferably in the upper end portion thereof, there is placed a body 41 of sound-absorptive material in accordance with my Patent No. 2,380,845. Leading from the chamber 40 through the side wall of the valve and at a small distance below the body 41 is a series of graduated openings spaced angularly about the axis of the valve at the level of the outlets 25 and 26, these openings comprising for example a large opening 42 and a series of three successively-smaller openings 43, 44 and 45. The larger opening 43 of the series 43-45 is spaced approximately 120° clockwise from the opening 42 and the openings 44 and 45 are spaced successively at approximately 45° intervals from the opening 43 (Figure 5).

Upon turning the valve into its most counter-clockwise position the opening 42 is aligned fully with the outlet 25 to the horn, but the series of openings 43-45 are closed by the wall of the housing. Thus, in this position of the valve, the reproduced sounds are transmitted to the horn at maximum loudness level. This position of the valve is indicated visually by the registration of a dot 46 on the rib 37 of the valve with the letter L (representing Loud) on the frusto-conical face 34 of the housing. Upon moving the valve clockwise from this position through a range of approximately 40° the opening 42 is moved progressively out of alignment with the outlet 25, while the openings 43-45 remain closed, to reduce gradually the volume of sound transmission to the horn. Two successive positions of the valve which give medium and low levels of sound transmission to the horn are indicated by the registration of the dot 46 with the letters M and S (M standing for Medium and S for Soft) on the face 34. Upon moving the valve further clockwise about 10° beyond the 40° range above-noted, the opening 42 is totally closed and the smallest of the series of openings 43-45 is aligned with the outlet 26 to the headset. Thus the reproduced sounds are now transmitted only to the headset at minimum level. As the valve is moved further clockwise by 45° intervals the next openings 44 and 45 are aligned successively with the outlet 26 to increase the level of transmission to the headset to Medium and Loud respectively. These low, medium and loud positions of the valve with respect to the headset are located by the registration of a second dot 47 on the rib 37 with the numbers 1, 2 and 3 respectively on the face 34. In order that the relation of the dots 46 and 47 to the characters on the face 34 may not be confused, the dot 46 and associated characters L, M and S are printed in one color and the dot 47 and associated numbers 1, 2 and 3 are printed in another color.

In the foregoing description, it will be understood that the valve has one range of movement for coupling the horn to the reproducer and for modifying the volume and tonal character of the sounds transmitted to the horn, and has another range for coupling the headset to the reproducer and for modifying the volume and tonal character of the sounds transmitted to the headset.

As the volume level is increased, the level of the higher-frequency sounds to that of the lower is increased. This provides a tone control with change in volume which is desirable in transcribing recorded matter because it enables the operator to adjust the tonal quality and volume, particularly in relation to the record surface noise, to adjust the volume and tone of the reproduced sounds for maximum speech intelligibility.

It may be noted that in the Loud (3) position of the valve with respect to the headset—the position wherein the opening 43 registers with the outlet 26—the smallest opening 45 registers with the outlet 25 to the horn. The opening 45 is however so small relative to the opening 43 that no appreciable sound is transmitted to the horn; however, by permitting the opening 45 to register with the outlet 25 in this position of the valve a more advantageous positioning of the outlets and of the control positions of the valve is obtained.

As a means for providing a drag on the valve to hold it frictionally in its adjusted positions, a compression spring 48 is inset in the head portion 25 of the valve so that it will bear slidably against the bevel face 33 of the housing as indicated in Figure 4.

It is desirable that the sound chamber 40 be vented to the outside whenever the escape vents for the sound to the horn or headset are small. For this reason such venting is provided in the M and S positions of the valve with respect to the horn and in all positions of the valve with respect to the headset. In the M and S positions the venting is provided by a fractional alignment of the opening 43 in the valve with an opening 50 in the housing; in the number 1 position of the valve with respect to the headset it is provided by the alignment of an opening 51 in the valve with an opening 52 in the housing; and in number 2 and number 3 positions of the valve with respect to the headset it is obtained by a fractional alignment of the opening 42 with the opening 50.

I have hereinabove particularly described a preferred embodiment of my invention but this embodiment is intended to be illustrative and not necessarily limitative of my invention as the same is subject to changes and modifications without departure from the scope of my invention, which I endeavor to express according to the following claims.

I claim:

1. In a sound control device for selectively coupling a source of sound to a plurality of sound receivers: the combination of a housing having an internal cylindrical cavity connected to said source and having a pair of outlet ducts leading from said cavity and coupled to said receivers respectively; and a valve in said cavity rotatably fitting said housing, said valve having one opening approximately the size of one of said ducts positioned for registration with said one duct within only one angular range of turning movement of the valve relative to the housing, and said valve having additionally a series of openings of graduated size each smaller than the other of said outlet ducts and positioned at intervals about the axis of the valve for selective registration with the other of said ducts within only another angular range of turning movement of the valve separate from the aforesaid one angular range, said valve fitting said housing snugly to close substantially said other outlet duct when the valve is within said one range and to close substantially

said one outlet duct when the valve is in said other range.

2. In a sound control device for selectively coupling a source of sound to a plurality of sound receivers: the combination of a housing having an internal cylindrical cavity connected to said source and having a pair of outlet ducts leading from said cavity and coupled to said receivers respectively, said outlet ducts being in a common medial plane transverse to the axis of said cavity and being positioned substantially 90° from each other about said axis as a center, and a tubular valve fitting said cavity for rotation relative to said housing, said valve having one opening registrable with said one outlet duct within a first rotational range of turning movement of the valve less than a right angle, means limiting movement of the valve in one direction to a position wherein said first opening is in substantially full registration with said one duct, and said valve having a series of openings of graduated size spaced at intervals from said one opening for successive registration with said other duct as

said valve is turned from said limit position to positions wherein said one opening is out of registration with said one duct, the order of registration with said other duct being from the smaller to the larger of said openings as the valve is turned in the direction away from said limit position, and said series of openings being wholly out of registration with said other duct in all positions of said valve wherein said one opening is in registration with said one outlet duct.
